US00D829225S

(12) **United States Design Patent** (10) Patent No.: **US D829,225 S**
Gandhi et al. (45) Date of Patent: **** Sep. 25, 2018**

(54) **DISPLAY SCREEN WITH GRAPHICAL USER INTERFACE**

(71) Applicant: **ADP, LLC**, Roseland, NJ (US)

(72) Inventors: **Rajiv Gandhi**, New York City, NY (US); **Angelynn Nakaguchi**, Jackson Heights, NY (US); **Eric Stolten**, Summit, NJ (US); **Torgeir Helgevold**, New York City, NY (US); **Melissa Scano-Person**, Union City, NJ (US); **Anthony Amendola**, Jersey City, NJ (US); **Serafin Vazquez**, New York City, NY (US); **Agnes Marcinkik**, Guttenberg, NJ (US); **Vinitha Kontham**, Edison, NJ (US); **Jason Lin**, Hollis Hills, NY (US)

(73) Assignee: **ADP, LLC**, Roseland, NJ (US)

(**) Term: **15 Years**

(21) Appl. No.: **29/545,523**

(22) Filed: **Nov. 13, 2015**

(51) LOC (11) Cl. **14-04**

(52) U.S. Cl.

USPC **D14/486**

(57) **CLAIM**

The ornamental design for a display screen with graphical user interface, as shown and described.

DESCRIPTION

FIG. 1 is a front view of a first embodiment for a display screen with graphical user interface;

FIG. 2 is a front view of a second embodiment for a display screen with graphical user interface; and,

FIG. 3 is a front view of a third embodiment for a display screen with graphical user interface.

The broken line showing of the display screen and portions of the graphical user interface is included for the purpose of illustrating portions of the article and forms no part of the claimed design.

1 Claim, 2 Drawing Sheets
